UNITED STATES PATENT OFFICE.

THOMAS D. HOOPER, JR., OF PHILADELPHIA, PENNSYLVANIA.

AMUSEMENT APPARATUS.

1,360,953.

Specification of Letters Patent. Patented Nov. 30, 1920.

Application filed May 1, 1920. Serial No. 378,297.

To all whom it may concern:

Be it known that I, THOMAS D. HOOPER, Jr., a citizen of the United States, residing at the city of Philadelphia, county of Philadelphia, and State of Pennsylvania, have invented a certain new and useful Improved Amusement Apparatus, of which the following is a specification.

The present invention has relation to and 10 is an improvement upon the apparatus set forth in Letters Patent Number 1,101,630 granted to me June 30, 1914. According to the construction of parts as shown and described in said patent it is necessary to employ a double set of traction rails which adds materially to the erection and maintenance costs of the apparatus. I have discovered that a conventional scenic railway may be readily converted into a structure embodying features of the present invention by making use of the single set of tracks found thereon and connecting therewith a series of loops and re-arranging the wheels of the 20 trucks as found upon a conventional scenic railway car so that the flanges of the wheels of one truck track upon the outer edges of the single line of rails and the flanges of the wheels of the other truck track upon the inner edges of said rails. The effect of this 25 is to render any scenic railway readily adaptable for conversion into a novel amusement apparatus at comparatively little cost and practically no added maintenance cost. I have also discovered that when a car-body 30 is reversing at a loop that there is a tendency of the car to tilt and in the present instance I have provided means upon both the car and adjacent a loop for reducing such tilting to a minimum.

40 The invention consists of the improvements hereinafter described and finally claimed.

The nature, characteristic features and scope of the invention will be more fully understood from the following description taken in connection with the accompanying drawings forming part hereof, and in which:

Figure 1, is a view in cross-section of an incline of a scenic railway of the present 50 invention taken at one of the loops thereof.

Fig. 2, is a fragmentary view, in plan, of an incline including loops, the supporting structure being omitted for the sake of clearness, and

55 Fig. 3, is a view in plan of a car illustrating the non-tilting device as applied thereto.

For the purpose of illustrating my invention I have shown in the accompanying drawings one form thereof which is at present preferred by me, since the same has 60 been found in practice to give satisfactory and reliable results, although it is to be understood that the various instrumentalities of which my invention consists can be variously arranged and organized and that 65 my invention is not limited to the precise arrangement and organization of the instrumentalities as herein shown and described.

In the drawings a scenic railway is shown for illustrative purposes although obviously 70 the present idea may be readily embodied in the form of a toy. Since the construction of scenic railways is well understood in the art I have shown no more thereof in the drawings than is necessary to an understanding of the present invention. 10 designates cross-ties and 11 bucks of an incline of a conventional scenic railway. 12 designates the conventional single set of rails as mounted upon the cross-ties 10. At an appropriate place or places along the incline 75 the cross-ties are extended beyond the line of the track as at 10' upon which a loop 13 is constructed. In practice such loops are positioned in pairs one upon each side of the 80 main line of rails although this is not essential. It however provides for the comfort of the patrons of a scenic railway as will hereinafter be described. Adapted for travel over an incline, under the influence 85 of gravity, are cars 14 each provided with a pair of trucks 15 having swiveled relation as at 16 with a car. Each truck is usually equipped with four wheels and the flanges thereof are similarly positioned as shown in 90 my patent aforesaid. By the present invention, however, I reverse the wheels of one truck so that instead of the flanges thereof 95 engaging the outside edges of the rails they engage the inner edges of the rails. By this 100 arrangement I am enabled to obtain a reversal of car-body at a loop to produce a sensation both novel and exhilarating in its effect. This reversal of car-body is made possible for the following reason:—For the 105 sake of illustration, let it be assumed that the flanges of wheels of the truck at the front of a car track upon the outside edges of the rails of an incline and that the flanges of the wheels of the rear truck track upon 110 the inside edges of the rails and let it be further assumed that such front truck is to

take the first loop. This arrangement of parts is shown in Fig. 2. It will be observed that the front truck in taking the loop has a greater distance to travel than does the rear truck passing along the main line of the rails so that the rear truck overtakes the front truck and temporarily becomes the leading truck. By the exchange of places the body of the car, because of its swiveled 10 connections with said trucks, has been shifted end for end so that the passengers therein are now seated backward. To promote the comfort of the occupants of the car, it is desirable to immediately re-shift the 15 car-body and preferably upon the opposite side of the main rails so that said passengers shall not be subjected to dizziness. The car is re-shifted by reason of another loop and it will be observed that the wheels of the 20 rear truck (now the leading truck) follow the rails of the loop while the wheels of the rear truck (now the trailer) follow the main line of rails so that the car is caused to assume its former position, that is, with the 25 passengers seated forward.

In order to prevent tilting of a car during the above described shiftings both the cars and the bucks may be provided with means tending to reduce tilting to a minimum. 30 Each truck may have fixed thereon a horizontally disposed plate 17 and adapted to bear upon each plate are a pair of rollers 18 secured to the underside of a car. With the rollers so positioned two are upon the 35 left hand side of a car and two upon the right hand side of a car. A car in shifting end for end as it passes through a loop moves "cross-wise" of the rails while the trucks retain their same relative position. 40 In this position the rollers 18 bearing upon the plates 17 of the trucks serve to maintain the body of a car in a non-tiltable position. As an additional preventive the bucks 45 may be provided with a guard rail 19 for a loop and a guard rail 20 for a main line opposite a loop. The ends of a car pass under such guards during shifting. In order to provide clearance with respect to the bucks the ends of the car are rounded as 50 illustrated.

It will now be apparent that I have devised a novel and useful construction which embodies the features of advantage enumerated as desirable in the statement of the 55 invention and the above description and while I have in the present instance shown and described the preferred embodiment

thereof which has been found in practice to give satisfactory and reliable results, it is to be understood that the same is susceptible 60 of modification in various particulars without departing from the spirit or scope of the invention or sacrificing any of its advantages.

What I claim is:—

1. In an amusement apparatus, an incline provided with a single set of traction rails, loops arranged at intervals along the line of said rails, a car adapted for travel over said rails under the influence of gravity and trucks having swiveled relation with said car, one truck being provided with flanged traction wheels the flanges of which are arranged to track upon the inside edges of 70 said rails and the other truck being provided with flanged traction wheels the flanges of which are arranged to track upon the outside edges of said rails whereby when a loop is reached one of said trucks follows the main line of rails and the other truck 80 follows a loop line of rails whereby said car is shifted end for end without changing its original course of travel.

2. Apparatus as described in claim 1, characterized by a guard juxtaposed to the 85 outer rail of a loop and a guard juxtaposed to the outer rail of the main line opposite to the first mentioned guard to preclude tilting of said car during shifting of its 90 position.

3. Apparatus as described in claim 1 characterized by means arranged between a truck and said car to prevent tilting of said car during shifting of its position.

4. In amusement apparatus, an incline 95 provided with a single set of traction rails, loops arranged at intervals along the line of said rails, a car adapted for travel over said incline under the influences of gravity and trucks having swiveled relation with 100 said car, one truck being provided with flanged traction wheels, the flanges of which are arranged to first follow the main line of rails and then follow a loop and the other truck being provided with flanged traction 105 wheels, the flanges of which are arranged to continue along said main line of rails and follow the next loop whereby said car upon reaching a loop is caused to be shifted end for end without changing its original course 110 of travel.

In testimony whereof I have hereunto signed my name.

THOMAS D. HOOPER, JR.
